DESIGN FOR AN ARMCHAIR

Frederick T. Paden, United States Army,
Collingswood, N. J.

Application April 18, 1945, Serial No. 119,077

Term of patent 7 years

(Cl. D15—1)

To all whom it may concern:

Be it known that I, Frederick T. Paden, Army of the United States, a citizen of the United States, residing at Collingswood in the county of Camden and State of New Jersey, have invented a new, original, and ornamental Design for an Armchair, of which the following is a specification, reference being had to the accompanying drawings, forming a part thereof.

Fig. 1 is a side elevational view of an armchair showing my new design.

Fig. 2 is a rear elevational view of the armchair.

Fig. 3 is a front elevational view of the armchair.

Fig. 4 is a top plan view with a portion of the armchair cut away to more clearly illustrate certain design features thereof.

Fig. 5 is a top perspective view of the armchair with the cushion removed to more clearly illustrate the design of the framework of the chair.

The characteristic features of my design are shown my means of full lines in the drawings.

I claim:

The ornamental design for an armchair, as shown and described.

FREDERICK T. PADEN.
